UNITED STATES PATENT OFFICE.

WILLIAM P. DAVIS, OF WARREN, AND HENRY J. ALEXANDER, OF HUNTINGTON COUNTY, INDIANA.

SWINGING GATE.

SPECIFICATION forming part of Letters Patent No. 604,110, dated May 17, 1898.

Application filed November 15, 1897. Serial No. 658,590. (No model.)

To all whom it may concern:

Be it known that we, WILLIAM P. DAVIS, residing at Warren, in the county of Huntington, and HENRY J. ALEXANDER, residing 5 in Huntington county, State of Indiana, citizens of the United States, have invented certain new and useful Improvements in Swinging Gates; and we do hereby declare the following to be a full, clear, and exact description 10 of the invention, such as will enable others skilled in the art to which it appertains to make and use the same.

This invention relates to opening and closing apparatus for swinging gates, and is particularly adapted for use in connection with 15 farm-gates, which it is a great convenience to be able to open and close without dismounting from a vehicle or from horseback.

The present invention has relation more 20 particularly to that type of such apparatus in which the actuating devices are arranged overhead to be manipulated by hand; and the principal object of the invention is to provide a construction whereby a reciprocatory movement 25 of an overhead actuator is converted into a complete swing of the gate to open or close the same, so that the same position of the actuator obtains whether the gate be open or closed, and the operator manipulates the 30 apparatus in exactly the same way when opening the gate as when closing the same—*i. e.*, by a reciprocatory movement of the actuator.

With the above-stated objects in view the invention consists in certain novel features of 35 construction and combinations of parts, all of which will be hereinafter specifically described, and the essential elements thereof pointed out in the appended claims.

The drawings which accompany and form 40 part of this specification illustrate a form of embodiment of the invention.

Of said drawings, Figure 1 represents the complete apparatus, in perspective, in connection with a swinging gate, which is shown as 45 closed. Fig. 2 represents the same in plan. Fig. 3 represents the middle portion of the apparatus in perspective, illustrating on a larger scale than Fig. 1 the relative positions of parts when the gate is closed. Fig. 4 represents, in sectional perspective, the same portion 50 of the apparatus as shown in Fig. 3, the

parts appearing in the relative positions they assume when the gate has been opened part way. Figs. 5 and 6 represent, partly in section and partly in elevation, certain of the 55 parts shown in Fig. 3, illustrating the same in different relations which they assume under different positions of the gate. Fig. 7 represents a detail of the gate member of the lower hinge, and Fig. 8 represents a detail of 60 the post member of the upper hinge.

In the drawings the reference-letter A designates a swinging gate, of any suitable construction, supported between two posts B and B', the shorter one of which is provided with 65 a suitable latch-slot b, while the taller post supports hinge members of the following description: The upper hinge member on the post consists of an elongated staple or loop b², having its ends passed through the post and screw-threaded for the reception of nuts, the said loop or staple being shouldered, as at b³, to hold its vertical portion at such a distance from the post as to permit a free movement both vertically and rotatably of a screw-eye 70 b⁴, which embraces the said vertical portion of the loop and is fastened in the inner upright of the gate. There are two lower hinge members shown as fastened to the post B, each consisting of an angle-iron with a horizontal arm c passing through the post and screw-threaded for the reception of a nut and an upstanding arm c' having a flattened projection or nib c² on one side at the top. The inner post of the gate has secured in it near 75 its lower end a hinge member in the form of a screw-eye c³, with a keyhole-shaped opening c⁴ in its horizontally-flattened head, corresponding with the formation at the upper end of each lower hinge member on the post B. 80 The construction of the lower hinge member on the gate is clearly illustrated in Fig. 7, and by reference to Fig. 3 it will be clearly seen that the form and construction of these lower hinge members permits the one on the gate 85 to be slipped down over the upstanding arm of either member on the post B, so as to rest against the horizontal arm thereof, in which position it is free to turn on said upstanding arm, and the gate will have to be turned to a 90 certain position before the lower hinge members can be disengaged by lifting the gate.

Thus accidental displacement of the gate, by hogs rooting under it or other causes, is effectually guarded against. Two lower hinge members are provided on the post B, so that 5 the gate may be supported in an elevated position in bad weather, the construction of the upper hinge, as above described, permitting a vertical movement of the gate, as will be apparent, and the latch-slot *b* in the post B' being correspondingly elongated for the same purpose.

The latch *d* is of the sliding variety and is supported on rollers *d'* and held in latching position by a spring *d''*. The connections for 15 withdrawing the latch against the stress of said spring by the operation of the gate-opening mechanism will be described hereinafter.

The post B is suitably braced by tie-rods *e* and *e'*, the latter being fastened at one end to 20 an anchor *e''*, embedded in the ground, and being screw-threaded at its opposite end, which passes through the post, so that it may receive a nut *e'''*, provision being thus made for adjustment of the post to compensate for 25 sagging of the gate.

The actuator for the gate opening and closing apparatus is here shown in the form of an elongated frame, comprising a bar *f*, extending at right angles to the gate in its closed 30 position and on either side of the post B, to the rear side of which said bar is pivotally connected, as shown at *f'*, the said bar being also pivotally connected at or near its ends to supplementary or auxiliary posts *B''* and 35 *B'''*. This bar is here shown connected with the posts by means of interlocked staples; but the connection may be effected in any suitable manner which will permit a rocking movement of the bar. Trusses *f''* extend 40 across and are fastened to the bar *f*, the said trusses being disposed at opposite inclinations to each other and being fastened together at the point *f'''* and one of them having a portion *f''''* extending beyond said point 45 of connection and braced by a cross-bar *f'''''*, fastened to its end and also to the other truss and to the bar *f*. To further strengthen the framework at this point and to provide a support for parts hereinafter mentioned, the short 50 cross-piece *f''''''* is extended between the cross-piece *f'''* and the truss *f''*, which fastens to the latter. The outer or end portions of the actuator-frame are braced by bars *f''''*, extending between the ends of the longitudinal bar *f* and the outer portions of the trusses *f''*. Depending from the extremities of the latter are pull-rods or handles *f''''''*, conveniently located for manipulation by any one seated in 55 a vehicle or riding horseback.

60 Reverting to the central portion of the actuating-frame, with reference more particularly to Figs. 3 to 6, it will be observed that the short cross-piece *f''''''* is in a much higher plane than the truss extension *f''''*, and between these 65 two members of the frame there are extended a pair of rods *g* and *g'*, which constitute shoulders or abutments, as will hereinafter appear,

and are of sufficient extent to allow vertical play of members, hereinafter described, with which they coact. Guiding-rods *g''* and *g'''* depend from the cross-piece *f''''*, parallel with the bars *g* and *g'*, to properly confine the members, hereinafter described, with which the latter coact. A plate *h* is fastened across the truss extension *f''''* and the lower end portion 70 of the cross-bar *f'''*, the upper edge *h'* of said plate constituting a horizontal shoulder or abutment for coaction with the same members above referred to as coacting with the rods *g* and *g'*. These members are in the 80 form of bars *i* and *i'*, set on edge and extending between the bars or rods *g* and *g''* and *g'''*, respectively, and arranged to rest by gravity against the edge *h'* of the plate *h*. These bars *i* and *i'* are constructed at their 85 inner ends for coaction with the said plate and the rods *g* and *g'* in a manner which will be presently described, and at their outer ends are connected with the gate, the points of connection with the latter being in different radial lines from the hinging-center thereof.

At the inner ends of the bars *i* and *i'*, beyond the rods *g* and *g'*, studs *i''* and *i'''* project from the outer side of the bars for the abutment 95 or abuttal thereagainst of said rods *g* and *g'*, respectively, and the under edges of the bars are notched to form shoulders *i''''* and *i'''''* for the abutment or abuttal thereagainst of the front edge *h'* of the plate *h*. On the inner 100 sides of the bars *i* and *i'*, at the extremities thereof, there are fastened obliquely-set cams *i''''''* and *i''''''*, wedge-shaped in cross-section and rounded on their upper and lower edges.

The outer end of the bar *i*, which extends 105 in a lower plane than the outer end of the bar *i'*, is loosely coupled to a pendent arm *j* of a rock-shaft *j'*, which extends substantially at right angles to the gate and is journaled at one end in a screw-eye *j''*, fastened 110 in the inner upright of the gate, and at the other end is journaled in a bracket composed of a horizontally-extending member *j'''* and a vertically and obliquely extending member *j''''*, the latter extending downwardly from the 115 rock-shaft and then obliquely to the bottom of the inner post of the gate and constituting a guard to protect the apparatus from accidental displacement, as by stock rubbing against it. The said pendent arm *j* projects 120 from the rock-shaft near its outer end for connection with the bar *i*, whereas bar *i'* is loosely coupled at its inner end with an upstanding portion *j''''* of an arm *j'''''*, projecting from the rock-shaft near the inner end 125 thereof. A brace *j'''''* extends between the arm *j''''* and the rock-shaft, as clearly shown in Figs. 2 and 3.

The relative location of the points of connection between the bars *i* and *i'* and the gate 130 is best illustrated in Fig. 2, from which it will be observed that the bar *i* connects with the gate in a line substantially at right angles to the latter, whereas the bar *i'* connects with

the gate at a point more nearly in alignment therewith. It will therefore be seen that a swinging movement of the gate in one direction, effected by a movement of the bar *i* in the same direction, can be continued by a movement of the bar *i'* in the opposite direction, this by reason of the above-described relation of the points of connection of the two bars to the hinging-center of the gate.

10 It may be here stated that the rock-shaft *j'* is provided with a short arm *j*⁸, which depends for connection with a rod *k*, extending longitudinally through suitable openings in the gate and being connected at its forward end with the latch *d* for the purpose of withdrawing the latter when the bar *i* is moved in a direction to open the gate, a slight movement of the rock-shaft *j'* being permitted to accomplish this, limited by a loop *j*⁹ on the gate, embracing the arm *j*⁸.

15 In Figs. 1, 2, and 3 the parts are shown in the relation which obtains when the gate is closed, and it will be noted that the stud *i*² of the bar *i* lies immediately behind the abutment-rod *g*, and, moreover, a shoulder *i*⁴ in the under edge of the said bar *i* lies in front of the edge *h'* of the plate *h*. It will further be noted that the bar *i'* is projected some distance past the abutment-rod *g* and its lower edge rests upon the plate *h* outwardly beyond the shoulders *i*⁵.

20 The operation of the apparatus may be described as follows: To open the gate, a downward pull is first exerted upon either of the handles *f*⁸, which has the effect of rocking the actuator-frame in a direction to move its central portion upwardly and away from the gate. This causes the abutment-rod *g* to act against the stud *i*², and thereby exert a pull 25 upon the bar *i*, which pull is first transmitted to the rock-shaft *j*, effecting a sufficient movement thereof to release the latch through the connections described, and thereafter has the effect of swinging the gate part way open. 30 This movement of the actuator-frame carries the cam *i*⁶ over the upper surface of the cam *i*⁷, as illustrated in Fig. 4, where the gate is represented as in a partially open position. The effect of the cam *i*⁶ riding upon the cam 35 *i*⁷ is to elevate the former, and consequently the bar *i*, so that the shoulder *i*⁴ of the latter is disengaged from the plate *h*. Just before or just at the time this takes place the upper edge of the plate *h* passes one of the shoulders *i*⁵ of the bar *i'*, and the latter drops and assumes the position illustrated in Fig. 4, with 40 one of its shoulders in front of the edge *h'* of the plate *h*. The operator having executed the downward pull on the handle *f*⁸ to bring about the operations just described immediately pushes upward on the said handle, thereby effecting a reversal of movement of the actuator-frame. The resulting downward movement of the central portion of said frame causes the plate *h* to act against the shoulder *i*⁵ of the bar *i'*, moving the latter to complete 45 the opening of the gate through its connec-

tions therewith, it being understood that the points of connection between the bars and the gate are at this time on opposite sides of a plane embracing the hinging-center of the gate and the point of engagement of either of the bars with the actuator-frame. On the completion of the opening of the gate the relation of parts is as illustrated in Fig. 5, the 50 stud *i*³ of the bar *i'* lying immediately behind the rod *g*', whereas the bar *i* is projected considerably beyond the rod *g*. The closing of the gate is effected by the same manipulations of the actuator-frame as were pursued in the 55 opening of the gate. It will be observed that a downward pull upon either handle *f*⁸ causes the rod *g*' to act against the stud *i*³, and thereby impart movement to the bar *i'* in a direction to close the gate; but this manipulation of 60 the actuator only part way closes the gate. The cam *i*⁷ then rides upon the cam *i*⁶, as illustrated in Fig. 6, and thereby the bar *i'* is elevated to disengage its shoulder *i*⁵ from the plate *h*, and the bar *i* resumes its first position with one of its shoulders *i*⁴ in front of the edge *h'* of the plate *h* and its stud *i*² immediately behind the abutment-rod *g*. An upward movement of the handle *f*⁸ completes the closing of the gate, such manipulation of 65 the handle effecting a downward movement of the central portion of the actuator-frame, and consequently causing the plate *h* to act against the shoulder *i*⁴ of the bar *i*, and thereby impart such movement to the latter as to effect a completion of the closing movement 70 of the gate.

75 It will thus be seen that we have provided a double set of connections between a rocking actuator and a swinging gate, with provisions for alternating the operative engagement between the members or sections of such double set of connections and the actuator, so that by a reciprocatory movement or manipulation of the actuator the gate may be caused to execute a complete swing in either a closing or an opening direction, and when the gate has been fully opened the position of the actuator is the same as when the gate is closed. Of course it will be understood that the weight 80 of the parts on the rear side of the post B may be sufficient to effect the completion of movement of the gate, so that the operator need only pull downward upon either handle *f*⁸ and then release his hold upon the same.

85 It is evident that the construction and arrangement of parts here shown and described are susceptible of a great many variations without departing from the spirit and scope of the invention, and hence we do not limit ourselves to the particular form of embodiment of the invention here illustrated.

90 Having thus fully described our invention, what we claim as new, and desire to secure by Letters Patent of the United States, is—

95 1. Mechanism for opening and closing a swinging gate, comprising a rocking actuator, and a double set of operating connections between the same and the gate with provisions

for automatic alternation, whereby reciprocation of the rocker may be converted into a complete swing of the gate in one direction, substantially as described.

5 2. Mechanism for opening and closing a swinging gate, comprising a rocking actuator, and a pair of connector-bars coupled with the gate in different radial lines from the hinging-center thereof, said actuator and bars having 10 coacting abutments and said bars having coacting cams to alternately disengage abutments thereof from abutments on the actuator, substantially as and for the purpose described.

15 3. Mechanism for opening and closing a swinging gate, comprising an elongated rocking actuator having a plurality of vertically-extending shoulders or abutments and a horizontally-extending shoulder or abutment, 20 connector-bars coupled with the gate in different radial lines from its hinging-center and arranged to bear upon the horizontal shoulder or abutment adjacent to the vertically-extending shoulders or abutments, said bars having lateral projections for engagement with the latter and shoulders for engagement with the horizontal shoulder of the actuator, and also having coacting cams to effect alternate disengagement of the bars from said horizontal shoulder, substantially as described.

30 4. Mechanism for opening and closing a swinging gate, comprising an elongated actuating rocker-frame obliquely disposed on elevated supports and having at or near its middle lower portion a horizontally-extending edge or shoulder and a plurality of vertically-extending abutments or shoulders adjacent thereto, a pair of connector-bars set on edge to rest upon the said horizontal shoulder and 35 having teeth or shoulders to alternately engage the same for movement of said bars in

one direction by the actuator, the bars having coacting cams to alternately disengage them from the said horizontal shoulder and also provided with lateral abutments or projections for engagement with the vertical abutments of the actuator to effect movement of the bars alternately in a direction opposite to that produced through their engagement with the horizontal shoulder, and arms projecting laterally and divergently from the gate at the hinged end thereof and pivotally connected with the bars respectively. 45

5. Mechanism for opening and closing a swinging gate, comprising a rocking actuator, 55 a double set of operating connections between the same and the gate with provisions for automatic alternation whereby reciprocation of the rocker may be converted into a complete swing of the gate in one direction, and a latch 60 on the gate coupled with the said connections, substantially as described.

6. Mechanism for opening and closing a swinging gate, comprising a rock-shaft on the hinge end of the gate and projecting laterally 65 therefrom and having a plurality of arms, a bracket fastened on the gate and supporting the outer end of said rock-shaft, said bracket comprising a member extending downwardly to constitute a guard for a pendent arm of 70 the rock-shaft, a latch on the gate operatively connected with an arm of the rock-shaft, a rocking actuator, and suitable connections between the same and the said rock-shaft.

In testimony whereof we affix our signatures in the presence of two witnesses. 75
